DESIGN FOR A BOTTLE

George M. Brenner, Oak Park, Ill., assignor to Bon Ton Beverages, Inc., Chicago, Ill., a corporation of Illinois

Application October 24, 1935, Serial No. 59,197

Term of patent 7 years

To whom it may concern:

Be it known that I, George M. Brenner, a citizen of the United States, residing at 724 Highland Ave., city of Oak Park, in the county of Cook and State of Illinois, have invented a new, original, and ornamental Design for Bottles, of which the following is a specification, reference being had to the accompanying drawing, forming part thereof.

The figure is a side view in elevation of a bottle, showing my new design.

The side not shown is substantially identical with the side shown in the drawing.

I claim:

The ornamental design for a bottle, as shown and described.

GEORGE M. BRENNER.
